UNITED STATES PATENT OFFICE.

HARRY ST. C. REYNOLDS, OF NEW HAVEN, CONNECTICUT.

ORDER-INDICATOR.

SPECIFICATION forming part of Letters Patent No. 743,397, dated November 3, 1903.

Application filed March 13, 1903. Serial No. 147,580. (No model.)

To all whom it may concern:

Be it known that I, HARRY ST. C. REYNOLDS, of New Haven, in the county of New Haven and State of Connecticut, have invented a new and useful Improvement in Order-Indicators; and I do hereby declare the following, when taken in connection with the accompanying drawings and the letters of reference marked thereon, to be a full, clear, and exact description of the same, and which said drawings constitute part of this specification, and represent, in—

Figure 1, a view in front elevation of an order-indicator constructed in accordance with my invention, showing one strip of spring-fingers upon each roll; Fig. 2, a side view of the same; Fig. 3, a broken front view of a section of spring-fingers detached and enlarged; Fig. 4, an edge view of the same; Fig. 5, a perspective view of a card or ticket adapted to be used in connection therewith; Fig. 6, a plan view of a section of spring-fingers formed from wire; Fig. 7, a top or edge view of the same.

This invention relates to an improvement in order-indicators—that is, an indicator adapted to receive cards or tickets representing numbers of orders received—whereby a convenient record may be kept of unfilled or partially-filled orders, and is an improvement on the invention for which Letters Patent of the United States No. 588,805 were granted August 24, 1897, to William H. Reynolds. In this patent two or more day-boards were employed and a month-board, the boards having holes arranged in series and adapted to receive pegs or pins having recesses in their outer ends for the reception of disks containing figures or characters to indicate orders, different-colored disks being employed to indicate orders which were partially filled.

The object of this invention is to arrange day and month boards in the form of drums or rollers and mount them one above the other in a standard in which they may be conveniently revolved; and the invention consists in the construction as hereinafter described, and particularly recited in the claims.

As herein shown, I preferably employ a standard comprising a base 2, uprights 3, 4, and top 5, the top connecting the upper ends of the uprights, which are also connected by

transverse bars 6, 7. The frame and bars may be formed from wood or metal, and preferably in the base 2 a drawer 8 will be located. Between the top 5 and the bar 6 is a shaft 9, carrying heads or disks 10, more or less in number, the shafts extending through the uprights and being provided at their outer ends with knurled finger-buttons 11. Secured to the heads are rows of clips or indicator-receivers 12, the number of rows depending upon the size of the indicator. In Fig. 1 only one row is shown to avoid confusion. In Fig. 2, however, eight rows are shown. Preferably twelve clips will be arranged in each row, and upon the lower edge of the top 5 numbers from "1" to "12" will be placed in line with the clips. These clips are preferably formed from strips of metal having fingers 13, 14, the fingers 14 being doubled upon the fingers 13, as clearly shown in Fig. 4. Between the transverse bars 6 and 7 a second shaft 15 is arranged, carrying heads 16 and being provided with thumb-buttons 17, and to these heads strips of clips 18 are attached. Between the bar 7 and the base 2 a third shaft 19 is arranged, carrying heads 20 and adapted to be turned by thumb-buttons 21. (While I have shown a number of heads or disks on each shaft, it is not essential that more than two be employed, these being arranged at opposite ends of the shaft.) To these heads strips 22 of clips are connected. Preferably I provide thirty-one clips on each strip on the two lower rolls, and the bars 6 and 7 are provided with numbers from "1" to "31," arranged in line with the clips carried by the rolls. I employ the term "rolls," as the heads with the strips of fingers constitute rolls or cages. These clips are adapted to receive cards or tickets 23, which may be of any desired color.

Instead of forming the clips or indicator-receivers from strips of metal, they may be formed from wire, as shown in Figs. 6 and 7, in which a strip of wire 24 is bent into a U shape and the lower portion of the U turned upward to form a finger 25, adapted to hold a card or ticket 23 in the same way as the metal fingers above described.

If desired, wires 26 may be arranged between the series of clips to separate the circumferential rows.

The system employed for the use of this device is similar to that employed in the above patent—namely, for the first month the upper day-roll will be used and tickets inserted in the first annular row of clips indicating the number of orders received that day. As the orders of this day are filled the tickets will be removed, or if the orders are partially filled the tickets will be replaced by another ticket bearing the same number but with a different color, and so on through the month. For the second month the lower day-roll will be used in the same way. At the beginning of the third month all the tickets remaining upon the first roll will be removed and placed in the first circumferential row of clips in the top or month roll and the first day-roll be used for the third month, and so on. By arranging the clips in the form of drums or rolls economy of space is secured and the rolls may be conveniently examined from time to time as required.

Having fully described my invention, what I claim as new, and desire to secure by Letters Patent, is—

1. An order-indicator comprising a frame, a day-roll and a month-roll, one arranged above the other and independently rotatable, said rolls provided with transverse rows of indicator-receivers and adapted to be freely revolved in the frame, substantially as described. 30

2. An order-indicator comprising a base, two uprights and a top, two transverse bars between the base and top, the top and transverse bars being suitably numbered, shafts mounted between said bars, top and base, heads mounted on said shafts and adapted to be turned thereby, clips secured to said heads and arranged in longitudinal and circumferential rows corresponding to, and in alignment with a series of numbers on the top and bars, substantially as described. 35 40

In testimony whereof I have signed this specification in the presence of two subscribing witnesses. 45
